UNITED STATES PATENT OFFICE

ERTLE L. HARRINGTON, OF SASKATOON, SASKATCHEWAN, CANADA

DESIGN FOR A BASE FOR LABORATORY SUPPORTS

Application filed October 10, 1930. Serial No. 37,215. Term of patent 14 years.

To all whom it may concern:

Be it known that I, ERTLE L. HARRINGTON, a British subject, resident of Saskatoon, Province of Saskatchewan, Canada, have invented a new, original, and ornamental Design for a Base for Laboratory Supports, of which the following is a specification, reference being had to the accompanying drawings, forming a part thereof, wherein—

Fig. 1 of the drawing is a perspective view of the base;

Fig. 2 is a top view of the base;

Fig. 3 is a side elevation thereof.

I claim:

The ornamental design for a base for laboratory supports as shown and described.

ERTLE L. HARRINGTON.
